UNITED STATES PATENT OFFICE

JOSEPH MANN, OF PHILADELPHIA, PENNSYLVANIA, ASSIGNOR TO UNION SPECIAL MACHINE COMPANY, OF CHICAGO, ILLINOIS, A CORPORATION OF ILLINOIS

FOLDER SUPPORT FOR SEWING MACHINES

Application filed March 31, 1926. Serial No. 98,751.

The invention relates to new and useful improvements in folders for sewing machines, and more particularly to the means for supporting the folder.

5 An object of the invention is to provide a support for a folder which is adapted to be attached to the work support of a machine at either side of the line of feed, and which is so constructed that the supporting 10 means for the folder does not in any way obstruct the view of the stitching point by the operator of the machine.

A further object of the invention is to provide a support for folders of the above 15 type, wherein the folder can be adjusted transversely of its longitudinal axis, lengthwise of its longitudinal axis, and also tilted for the purpose of properly positioning the folder relative to the presser foot and the 20 needles of the stitching mechanism.

These and other objects will in part be obvious and will in part be hereinafter more fully disclosed.

In the drawings which show by way of 25 illustration one embodiment of the invention—

Figure 1 shows a front end of a portion of a sewing machine with the improved folder and support therefor mounted thereon;

Fig. 2 is plan view of the folder and the support therefor, showing the support located at one side of the folder in full lines and at the other side of the folder in dotted 35 lines, also showing the guide for leading in the reinforcing strip, said guide being disposed on the same side of the folder as the support for the folder in full lines and on the opposite side of the folder in dotted 40 lines;

Fig. 3 is a view similar to Fig. 2, of the bottom of the folder, the supporting bracket only being indicated by broken lines;

Fig. 4 is a sectional view on the line 4—4 45 of Fig. 2; and

Fig. 5 is a sectional view on the line 5—5 of Fig. 2.

The invention is directed broadly to a support for folders preferably of the type 50 for folding a center plait. One of the pur-

poses of this improved support for a folder is to provide means whereby the folder support may be attached to the work support of the machine at either side of the line of feed, and another purpose of this improved support for the folder is to provide a support which is attached to the folder on the under side thereof so that the operator has a clear space over the folder in which to view the stitching point. To this end, the 55 support for the folder consists of a bracket having a projecting rod or arm, which bracket is capable of being adjustably attached to the under side of the folder, and is so attached to the under side of the folder that it may be removed and inverted so as to project from either side of the folder. This bracket is mounted in the support which is adapted to be attached to the work support of the machine, and this support 60 is capable of being attached to the work support at either side of the line of feed, and when so attached, have the same symmetrical relation to the line of feed and the needles. The projecting arm or rod on the 65 bracket extends into the sleeve on this support and can be adjusted back and forth in the sleeve or oscillated in the sleeve. The oscillations of the rod or arm are for the purpose of raising and lowering the front 70 end of the folder. The endwise movements of the rod or arm in the sleeve are for the 75 purpose of adjusting the folder transversely of this longitudinal axis. This support is attached to the work support by screws 80 and slots which are disposed parallel with the line of feed so that the folder can be adjusted bodily toward and from the needles in a direction parallel of the line of feed.

Referring more in detail to the drawings, 85 the folder consists of a body portion 1 preferably made from a flat sheet of metal folded into the form of a flat tube and having its edges secured together as indicated at 2. The walls of this flat tubular body portion 90 are closely and uniformly spaced so as to form a guiding channel for a strip 3. The side portions 4 and 5 of this tubular folder are gradually turned underneath the body portion of the folder. The inner edges of 95 100

these folded under portions are slightly spaced from each other, and are rigidly secured to a member 6 which serves in part to support the folder. This member 6 is provided with a groove 7 in its upper face and the lower wall 8 of the body portion of the folder is provided with a downwardly projecting rib 9 which is associated with this groove in the support for the folder. A reinforcing strip 10 is guided through the channel formed between the folded underneath portions of the folder and the central body portion thereof. The lower wall of the body portion of the folder has a projecting portion 11 which flattens the reinforcing strip after it leaves the folder and causes the edges thereof to be forced into substantial contact with the infolded portions of the fabric prior to the stitching thereof. The member 6 extends well up toward the receiving end of the folder, and has a bracket 12 attached thereto which serves as a leading-in guide for the reinforcing strip. The reinforcing strip passes through a slot 13 in this guide and along the under face thereof, and is inverted and caused to make a forty-five degree turn around the edge 14 of the bracket 12. Said edge 14 as clearly shown in Fig. 3 of the drawings is formed by bending the metal into a hollow bead, and said bead is disposed relative to the bracket so that the bracket may be inverted and attached to the folder so as to project on either side thereof. Said bracket is secured to the folder by the screws 12a. This invertible bracket 12 for the reinforcing strip per se forms no part of my invention, as my particular invention is directed to the supporting bracket for the folder, yet this bracket 12 is very useful in conjunction with my invertible supporting bracket, and in combination therewith is a part of my invention. Attached to the under side of the folder is a shank portion 15. This shank portion 15 is rigidly secured to the member 6 and provides a supporting means for the folder. The folder is adapted to be mounted on a bracket 16. Said bracket, as shown in Figures 2 and 3 of the drawings, is provided with a cylindrically projecting arm 17. The bracket has spaced supporting arms which are provided with slots 16', 16', and screws 18, 18 passing through these slots rigidly secure the bracket to the folder. It will readily be seen that this bracket 16 can be inverted and attached to the folder so that the cylindrically projecting arm 17 may extend to either side of the folder. This projecting arm is adapted to be mounted in a main support 19. Said support has a sleeve 20, which receives the cylindrical arm 17. This sleeve 20 is a split sleeve, and a screw 21 passing through the lugs in the sleeve, 65 will draw the split sleeve in gripping con-

tact with the arm 17. The main support 19 has a base member 22 which is provided with elongated slots 23, 23. The base members are adapted to be secured to the work support S of the sewing machine as shown in Fig. 1 of the drawings. This is accomplished by screws 24 which pass through the slots 23, 23 and are threaded into the work support. Through this slot and screw connection, the support may be adjusted toward and from the needles n, n, and thus the folder brought closer to the presser foot or moved away therefrom. The material is fed underneath the presser foot by an ordinary feeding mechanism, and of course, the line of feed is parallel with the length of the presser foot as viewed in Fig. 1.

Through the aid of the screws 18, the folder can be adjusted transversely of the line of feed. The folder can also be adjusted transversely of the line of feed by loosening the screw 21 and shifting the sleeve 20 on the cylindrical arm 17. Through the aid of the cylindrical arm 17 and sleeve 20, the front end of the folder can be raised or lowered relative to the presser foot. Through these adjustments referred to, the folder can be properly set relative to the needles. The main support on which the folder is mounted can also be placed at either side of the line of feed. When the support 19 is shifted from one side of the line of feed to the other, then the cylindrical arm 17 is placed in the sleeve from the other end thereof and the bracket 16 is inverted. This keeps the folder located centrally of the stitching mechanism.

It is obvious that minor changes in the details of construction of the bracket and supporting means can be made without departing from the spirit of the invention as set forth in the appended claims.

Having thus described the invention, what I claim as new and desire to secure by Letters-Patent, is—

1. In a sewing machine, a folder, a bracket having a projecting arm, means for securing said bracket to said folder whereby the same may be inverted and the arm positioned so as to project from said folder at either side thereof, a support in which said arm may be mounted, said support being adapted to be shifted from one side of the folder to the other and attached to the work support of the machine, said projecting arm being cylindrical, and said support having a sleeve to receive the same from either end thereof, and means for holding said arm in adjusted positions in said sleeve.

2. In a sewing machine, a folder, a bracket having a projecting arm, means for securing said bracket to said folder whereby the same may be inverted and the arm positioned so as to project from said folder at either side thereof, a support in which said

arm may be mounted, said support being adapted to be shifted from one side of the folder to the other and attached to the work support of the machine, said folder having 5 a guiding channel for a reinforcing strip, a guiding bracket for receiving the reinforcing strip fed thereto in a direction substantially at right angles to the line of feed, and for directing said strip into said channel, and means whereby said guiding bracket can be inverted so that said reinforcing strip may be received from either side of the folder.

3. In a sewing machine, a folder, a 15 bracket having a projecting arm, said bracket being constructed whereby the same may be inverted and attached to the folder so that the arm will project from either side of the folder as desired, means for securing 20 said bracket to said folder, a support having means for receiving said arm with the folder at either side of the support, and means for attaching the support to the work support of the machine.

25 4. In a sewing machine, a folder, a bracket having a projecting arm, said bracket being constructed whereby the same may be inverted and attached to the folder so that the arm will project from 30 either side of the folder as desired, means for securing said bracket to said folder, a support having means for receiving said arm with the folder at either side of the support, and means for attaching the support 35 to the work support of the machine, said means for receiving said arm being constructed so as to permit the folder to be adjusted laterally of the line of feed and tilted so as to raise or lower the front end 40 of the folder relative to the work support of the machine.

5. In a sewing machine, a folder, a bracket having a projecting arm, said bracket being constructed whereby the same 45 may be inverted and attached to the folder so that the arm will project from either side of the folder as desired, means for securing said bracket to said folder, a support having means for receiving said arm with the folder 50 at either side of the support, means for attaching the support to the work support of the machine, said means for receiving said arm being constructed so as to permit the folder to be adjusted laterally of the line 55 of feed and tilted so as to raise or lower the front end of the folder relative to the work support of the machine, and means whereby the support may be adjusted toward and from the stitching mechanism.

60 In testimony whereof, I affix my signature.

JOSEPH MANN.
